UNITED STATES PATENT OFFICE.

GEORGE CORMACK, OF PLANO, ILLINOIS, ASSIGNOR TO INDEPENDENT HARVESTER COMPANY, OF PLANO, ILLINOIS, A CORPORATION OF MAINE.

MUFFLER.

1,040,628.

Specification of Letters Patent.

Patented Oct. 8, 1912.

Application filed February 2, 1912. Serial No. 675,057.

To all whom it may concern:

Be it known that I, GEORGE CORMACK, a citizen of the United States, residing at Plano, in the county of Kendall and State of Illinois, have invented new and useful Improvements in Mufflers, of which the following is a specification, reference being had to the accompanying drawings, forming a part thereof.

10 The purpose of this invention is to provide an improved form of muffler for explosive engines which shall be effective in reducing the sound of the exhaust without causing material back pressure.

15 It consists of the features and elements described and shown in the drawings as indicated in the claims.

20 In the drawings:—Figure 1 is a medial section of a muffler embodying this invention, section being taken as indicated at line 1—1 on Fig. 2. Fig. 2 represents in plan one section of the device, this view being obtained by taking section at line 2—2 on Fig. 1. Fig. 3 is an enlarged detail section 25 taken at line 3—3 on Fig. 2. Fig. 4 is a partial end elevation of the device.

25 The muffler which is the subject of this invention is made up of a series of similar sections, A, preferably of cast metal, and placed in a pile or tier as indicated in Fig. 1. Each section is provided with two apertured bosses A¹, through which may be passed securing bolts, B, for properly holding the sections together. In addition to the series of sections, A, there are provided a top section, C, and a bottom section, D, which differ slightly in form from the intermediate sections, A. Each of the sections, A, consists, as may be noted by com-

40 parison of Figs. 1 and 2, of a boundary flange, A², and a transverse web or wall, A³, whose function is to act as a baffle plate in breaking up and distributing the force of the exhaust gas. The space within the boundary flange, A², which is not traversed by the web, A³, has the form of a circular opening, A⁴; through which communication is afforded between the several chambers formed by successive sections when assembled as in Fig. 1. The assembling of the sections, as may be noted from this figure, is such as to bring the webs, A³, of successive sections at opposite sides of the center line of the muffler, so as to render the passage-way formed by the openings, A⁴, a

very circuitous one. The height of the flange, A², is slightly less than the height of the bosses, A¹, which extend a little below the lower surface of the web, A³. Thus, when the sections, A, are assembled one on top of another there remains between each pair of them a considerable crevice, A⁵. To properly complete the support of one section upon another there is provided at each end of the section a downwardly extending lug, A⁶, whose depth is equal to the excess depth of the bosses, A¹; with the section resting upon the bosses, A¹, and the lugs, A⁶, it will be seen that the crevice, A⁵, is divided into four parts, which extend along the greater portion of the flange, A², and through these crevices it is expected that the exhaust gas will make its escape. The total exhaust opening provided by the crevices, A⁵, is sufficient to prevent any substantial amount of back pressure, and the circuitous passage formed for the gases by the arrangement of the baffle-plates, A³, is relied upon to a large extent to break up the force and noise of the exhaust.

25 The top and bottom sections, C and D, will be understood to resemble in outline the intermediate sections, A, but the bottom section is formed with a complete transverse wall, D¹, in place of the partial wall, A³, of the section, A. The top section has bosses, C¹, and lugs, C⁶, which correspond to the bosses and lugs of the intermediate sections, A, but this section has no baffle-plate, being formed instead with a top wall, C³, and a central opening, C⁴, designed for connection with the exhaust pipe of an engine..

I claim:

1. A muffler comprising a chamber having an inlet at one end, a series of baffle-plates extending alternately from either side of the chamber, and outlet openings in the side walls between the positions of said baffle-plates.

2. A muffler comprising a chamber having an inlet at one end, a series of baffle-plates extending alternately from either side of the chamber and past the middle of its width, and outlet openings in the side walls between the positions of said baffle-plates.

3. A muffler comprising a chamber made up of sections, including end sections and intermediate sections, each intermediate section comprising a peripheral wall and a

- transverse web extending over a portion of the area within said peripheral wall, one of the end sections having an inlet opening, the intermediate sections being slightly spaced apart from one another to form outlet openings between them and assembled with successive web portions at opposite sides of the central axis of the muffler chamber, and means securing the sections in place.
- 5 10 4. A muffler comprising a chamber made up of a series of sections, including end sections and intermediate sections, said intermediate sections each comprising a peripheral wall, a transverse web extending over
- 15 a portion only of the area within said wall,
- and spacing lugs formed on one edge of the wall for spacing apart the successive sections to form outlet crevices, the sections being assembled with successive web portions at opposite sides of the central axis of the 20 muffler chamber, and one end section having an inlet opening.
- In testimony whereof, I have hereunto set my hand at Plano, Ill., this 23d day of January 1912.

GEORGE CORMACK.
